United States Patent Office

Des. 203,328
Patented Dec. 28, 1965

203,328

SIGN

Gilbert W. Cupp, 2000 S. Osceola Way, Denver, Colo.

Filed July 6, 1964, Ser. No. 80,697

Term of patent 14 years

(Cl. D1—12)

FIG. 3.

FIG. 1.

FIG. 2.

FIG. 4.

FIG. 5.

FIGURE 1 is a front elevational view of a sign showing my new design;

FIGURE 2 is a right edge view thereof;

FIGURE 3 is a top plan view thereof;

FIGURE 4 is a bottom plan view thereof; and

FIGURE 5 is a rear elevational view thereof.

The left edge view is identical to the right edge view. I claim:

The ornamental design for a sign, as shown and described.
